APPARATUS FOR FEEDING WIRES

John F. Donovan and George Illingworth, East
Cleveland, Ohio, assignors to General Electric
Company, a corporation of New York

Application October 12, 1934, Serial No. 748,069

6 Claims. (Cl. 140—132)

Our invention relates to apparatus for feeding wire lengths and more particularly to apparatus for feeding leading-in wires for incandescent lamps and other like devices into machines for the manufacture thereof. Our apparatus is associated with the manufacture of stems for said devices which are made on machines comprising a plurality of heads or carriers which in their course of movement are brought before the apparatus of our invention. A stem machine of this type is shown in Fagan and Staudenmeir Patent No. 1,655,141. One object of our invention is to provide apparatus for feeding the longer and heavier type leading-in wires for incandescent lamps. Another object of our invention is to provide apparatus for feeding leading-in wires which carries said wires between the jaws of the stem machine and deposits said wires in a specific location therein. Another object of our invention is to provide wire feeding apparatus which holds a large quantity of wires and which can be reloaded without stopping said apparatus. One species of the apparatus of our invention is shown in the drawings and is described in the following 25 paragraphs.

In the drawings, Figs. 1 and 2 are top and side views of a wire feeding apparatus of our invention; Fig. 3 is an exploded perspective view of the wire picking and transferring jaws; and Fig. 4 is a perspective view of the parts of a stem machine head between which, and into which, the wires are fed.

As shown in the drawings, the leading-in wires 10 are fed from pockets 11 of the turret 12 to the stem machine head partially shown at 13 by the jaws 14 and 15 shown at the delivery position. The pockets 11 are open at the top and bottom and are attached to the turret at an angle. The leading-in wires are supported by the circular plate 16 attached to the turret 12 and tend to fall outward therefrom due to the angularity of the pockets. The leading-in wires in the pocket from which the feeding operation is taking place do not rest against the side of the pocket but fall against the plate 17 which is slotted at 18 and 19 so the wires falling therewith are separated from the remainder. Plate 17 is mounted on arm 20 extending from cap 21 on pipe 22 which is attached to pipe 23 and to facilitate the separation is agitated back and forth. The agitation results from movement of lever 24 which is attached to pipe 23 through arm 25 and is turned about a pin 26 in table 27 on which it is mounted by mechanism (not shown). Pipe 23 is attached to pipe 28 which is attached by blocks 29 and 30 to table 27 and turns in said blocks. In some instances

it has also been found desirable to agitate the wires by puffs of air emitted from holes in pipe 31 which is connected to and supported by cap 21. The air passes into the pipe 31 from passages in cap 21, pipes 22, 23 and 28, the latter pipe 28 being connected through pipe 32 and flexible hose 33 to a source of air controlled by a valve operated in cooperation with the complete apparatus. The turret 12 is mounted on shaft 34 which is supported by the base 35 on the table 27.

The segregated wires in slots 18 and 19 are carried into apertures 36 and 37 formed by the ends of the picking jaws 14 and 15 by a movement of said jaws toward said turret as they are then facing the turret. The jaws 14 and 15 are attached to levers 38 and 39 which, as shown in Fig. 3, are pivotally mounted on screw 40 extending from slide 41. The slide rests in ways in the head 42 of tubular post 43 in which it is held by plates 44 and 45 and which is located within slide 46. The forward movement of the jaws is brought about by rotation of cam 47, the ways of which are engaged by the roller 48 on pin 49 extending from slide 41. The cam 47 is mounted on the top end of shaft 50 in post 43 and slide 46 which is turned through a gear and mechanism (not shown) on the lower end thereof. On taking this position the jaws are closed, that is, the ends of levers 38 and 39 are drawn together by spring 51 extending between posts in each and the teeth in the ends of the jaws are moved together closing apertures 36 and 37 until a wire is gripped. The teeth in the jaws are so spaced that aperture 37 is slightly larger than aperture 36. This construction causes the closing movement to stop if a wire is gripped in aperture 36 leaving the wire in aperture 37 free, and causes movement to continue if no wire is found in aperture 36 until the wire in aperture 37 is gripped. The closing movement is brought about by rotation of cam 52 until the low part thereof is below rollers 53 and 54 on pins 55 and 56 in levers 38 and 39 respectively. The cam 52 is mounted on pin 57 which is held by slide 41 and by plate 58 on block 59 on said slide and is turned by rotation of gear 60 also on said pin. The gear 60 meshes with the rack cut in slide 61 which lies in ways in block 59 and in this instance is operated by engagement of roller 62 with lever 63. Lever 63 is fastened to slide 61 by screw 64. Lever 63 is attached to standard 65 by screw 66 and is operated by cam 67, the ways of which are engaged by roller 68 on screw 69. Cam 67 is attached to shaft 70 in standard 65 which is turned by rod 71 through swiveling stud 72 and arm 73.

Having gripped a leading-in wire, the jaws are now raised until said wire is free of the pockets and the other wires. An additional puff of air from pipe 31 is used to push back the other 5 wires so they do not stick to the one removed and are drawn up with it. The jaws are raised by movement of slide 46 which moves in ways in bracket 74 as directed by mechanism (not shown) operating gear 75. Bracket 74 supports 10 pin 76 on which gear 75 is mounted and is attached to table 21. The puff of air on the wire held by the jaws tends to cause it to swing outward in some cases so movement is prevented by the finger 77 which is mounted on post 78 15 extending from the bar 79 extending between sides of head 42.

The jaws are now turned through 180° into the position they are shown in Figs. 1 and 2, and are moved to a location above the stem 20 machine parts. These movements are both caused by a clockwise turning of shaft 50, the former movement occurring as the head 42 turns and the latter movement occurring while said head is stationary and cam 47 is turned. The 25 head 42 is rotated because of the friction with which collar 80 engages shaft 50 since it is drawn thereagainst by leaf spring 81, which is held by screws 82 and 83 extending from the head 42. The full movement of the head is reached as 30 stud 84 (Fig. 2) strikes pad 85 of the slide 46.

The return downward movement of jaws now occurs placing the apparatus parts in the position shown and the leading-in wire therein through the aperture in funnel 86 and the glass 35 flare tube 87. The release of the leading-in wire is then effected by lever 63 striking roller 88 on screw 89 of slide 61 and said wire falls through the aperture in funnel 90 and into the aperture in tube 81. During these operations, the jaws 40 92, 93, and 94 of the stem machine head, which are more clearly shown in Fig. 4, are separated so the wire may pass therebetween. Funnels 86 and 80 are comprised of two parts which are brought together and swing apart at the proper 45 time intervals with respect to the wire feeding and stem head movements. In the drawings, one part of the funnels is shown attached to the shaft 95 in bracket 74 whereas a similar arrangement exists but is not shown for the other part 50 of the funnels. Gears 96 on each shaft mesh together and are turned as required.

The feeding operation of the apparatus is repeated until in this case 200 of the 250 wires placed in the pocket 11 are removed whereupon 55 another pocket is indexed into position. This movement results from ratchet mechanism (not shown) and occurs as plate 17 is in the back position. The wire of the new pocket is guided into position before the plate 17 by guide wires 60 97 and 98, the former of which is supported by post 99 extending from the table 21. Wire 98 is mounted on arm 100 which pivots on pin 101 in bracket 102 and normally lies back away from the leading-in wires as shown. In the rest 65 positions of the turret 12, the roller 103 carried by arm 100 engages the teeth 104 in plate 16, but as the turret turns the roller comes over a low part thereof and the arm 100 and wire 98 is swung in by spring 105. The spring 105 is 70 located between spring posts in base 35 and arm 100. Wire 98 also withdraws the wires in the partially emptied pocket from the grooves of plate 16 so they may index out of position. Obviously other wire feeding apparatus of this type may be coupled to the apparatus described so as to 75

feed any other leading-in wires required for the lamp stem. Such apparatus must be located at other positions taken by the stem head into which the described apparatus feeds.

What we claim as new and desire to secure 5 by Letters Patent of the United States is:

1. An apparatus for feeding wires comprising a pocket for holding a quantity of wires, a plate with a groove in one edge adapted to hold one wire at the vertex thereof, means for carrying 10 the plate against the wires in the pocket so that they are carried into said groove, a pair of jaws adapted to grip the wire segregated by the groove, transferring means for moving said jaws to withdraw said wire from said pocket and to carry 15 it to a delivery position and means for closing and opening the jaws at pick-up and delivery positions.

2. An apparatus for feeding wires comprising a pocket for holding a quantity of wires, a plate 20 with a groove in one edge adapted to hold one wire at the vertex thereof, means for carrying the plate against the wires in the pocket so that they are carried into said groove, a pipe mounted adjacent said plate adapted to emit puffs of air 25 against the wires agitating them, a pair of jaws adapted to grip the wire segregated by the groove transferring means for moving said jaws to withdraw said wire from said pocket and to carry 30 it to a delivery position and means for closing and opening the jaws at pick-up and delivery positions.

3. An apparatus for feeding wires comprising a pocket for holding a quantity of wires, means for holding the pocket in an oblique position 35 so said wires fall to one side, a plate with a groove in one edge thereof adapted to hold one wire at the vertex thereof, means for carrying the plate against the reclining side of the wires so that they fall into said groove, a pipe mounted 40 adjacent said plate adapted to emit puffs of air against the wires to agitate them and to force the other wires back as the segregated wire is removed, a pair of jaws adapted to grip the wire segregated in the groove, transferring means 45 for moving said jaws to withdraw said wire from said pocket and to carry it to a delivery position and means for closing and opening the jaws at pick-up and delivery positions.

4. An apparatus for feeding wires comprising 50 a turret having a plurality of pockets mounted thereabout in a substantially vertical position for holding a quantity of wires, said turret being rotatably mounted so that it may be indexed to bring said pockets in succession to a discharge 55 position, means engaging the wires in each of said pockets at said discharge position for separating one of the wires from the remainder, a pair of jaws adapted to grip said wire, transferring means for moving said jaws to withdraw 60 the wire from said pocket and carry it to a delivery position and means for closing and opening said jaws at pick-up and delivery positions.

5. An apparatus for feeding wires comprising 65 a turret mounted and adapted to be indexed on a vertical axis, a plurality of substantially vertical pockets disposed about the periphery of said turret for holding a quantity of wires, said pockets having outwardly inclined outer walls, means engaging the wires in the pocket registering therewith for separating one of the wires from the remainder, means for transferring said wire to a delivery position in proper time relation to the operation of the separating means and means 70 for lifting the wires in another of said pockets 75

to a substantially vertical position as the turret is rotated so that the wires therein may be allowed to fall sideward against the separating means on registering therewith.

- 5 6. An apparatus for feeding wires comprising a turret adapted to be indexed, a plurality of substantially vertical pockets disposed about the periphery of said turret for holding a quantity of wires and shaped so that said wires are inclined to the vertical with their upper ends outermost, a plate with a groove therein shaped to hold only one wire at the base thereof mounted adjacent said turret, means for pushing back
- 10

toward the vertical the wires in each pocket as said pocket approaches said grooved plate and for then allowing them to fall thereagainst, a pair of jaws adapted to grip the wire which disposes itself at the base of the aforesaid groove, means for directing air pressure to force the other wires back from the wire at the base, means for moving said jaws to withdraw said wire from the pocket and to carry it to a delivery position and means for closing and opening the jaws at 10 pick-up and delivery positions.
